**ORGANS FOR GRASPING WOOF THREADS IN
INSERTING ELEMENTS OF STATIONARY WOOF
FRAMES**

The present invention relates to improvements in mechanisms for gripping and pulling weft threads through the shed of a loom.

Elements for inserting weft threads include a lance, rod or flexible strip, which is reciprocatorily moved through the shed of a loom to whose front end can be attached various types of mechanisms for gripping the weft thread, such as a hook, a loop or a clip.

These inserting elements usually need for operating the jaws that make up the weft thread gripping portion, complicated mechanisms in the area of gripping the weft thread at the mouth of the inserting element, or else must use remote controls; all of these are rather bulky and heavy, which cause difficulties in applying other elements that are vital for making cloth, such as selvage makers, cutting elements, suction elements, etc., and lead to difficulties in catching the weft threads, with the danger of damage to the warp threads when said mouths or jaws pass through the shed with their corresponding mechanisms.

The present invention aims at eliminating these drawbacks and the lack of safety by performing with absolute reliability the task of the gripping mechanism, by means of a device that is extremely simple and free of flaws, that does away completely with remote controls, that operates with great simplicity, that can be applied to any type of insertion element, whether they are rigid, for example, a rod or lance, or flexible, as for example a strip or band, and that in no way prevents the application of other elements that are vital for making cloth, such as selvage formers, cutting and suction elements, etc., while at the same time it does away with any danger of damage to the warp threads when the gripping element passes through the shed.

The device, which is the object of the present invention, is made up of a gripping mechanism with an elongated base like a bayonet which in the vicinity of its tip has attached a stop of yieldable material which makes up a stationary jaw, and approximately in the center of the length of said elongated base there is applied a pin which pivotally supports a two-arm lever, the end of the front arm of the lever serving to make the movable jaw press the weft threads against the yieldable stop, and the end of the back arm of said lever carrying a hinge joint for a rod, the free end of which is introduced so as to slide in a housing housed in a hinge joint of a member that is fixed to the lengthened base, the rod-hinge joint unit being actuated by a recoil helicoidal spring that automatically causes the oscillation movement of the lever in both directions, for opening and closing of the mobile jaw. Said bayonetlike elongated base is also covered with a protecting shield along its whole length, which prevents, as it passes through the shed, the elements of the gripping mechanism from grazing the warp threads and damaging them.

The end opposite the tip of the elongated base can be firmly attached to any type of inserter element, whether it is rigid, as for example, a rod or lance, or flexible, for example, a strip or band.

For a better understanding of the invention, there is described below, with reference to the accompanying drawings, an embodiment by way of nonlimiting example.

FIG. 1 is a perspective view of the gripping mechanism in open position to catch the weft thread, with the protector for the warp threads cut away along its entire length for greater visibility of the components.

FIG. 2 is a perspective view of the gripping mechanism of FIG. 1, also in closed position with the protector for the warp threads cut away.

FIG. 3 is a perspective view of the gripping mechanism corresponding to FIG. 2, but with the protector for the warp threads in place.

FIGS. 4 and 5 are details of the spring-rod unit in the open and closed positions of the mobile jaw.

FIGS. 6 and 7 are schematic plan views of the operation of the gripping mechanism on each side of the loom, with the protector for the warp threads cut away along its entire length for greater visibility of the components.

5 In these figures, the gripping mechanism comprises a lengthened bayonetlike shaped base, indicated by numeral 1 provided with lengthwise wings 2 and 3 bent at right angles along one side and with a lengthwise wing 4, also at right angles, but on the opposite side, the latter being bent again at right angles, at a slight distance above the base to overlie it in parallel relationship to constitute a protector 5 for the warp threads, having cutouts 6, FIG. 3, which besides eliminating weight, provide an outlet for dust or chaff which the repeated contact with the weft thread 7 can cause.

10 The base 1 and the wing 4 both terminate at the forward end in a point 8 and adjacent this end there is attached to the base a stop 9, made of a relatively yieldable material, positioned against the wing 4 to constitute the stationary jaw of the gripping mechanism. A lever 11, having opposing arms 12 and 13 is supported at a medial point for pivotal movement on a pin 10 attached to the base at a distance from its forward end 8. The arm 12 terminates in a slightly curved claw shaped portion 15 having an irregularly curved surface on its inner convex portion which coacts with a complementarily formed surface on the stop 9 to grasp a weft thread 7. The other arm 13 of the lever terminates in a horizontal flat surface 16 having a margin on the outwardly facing side which tapers inwardly (for a purpose which will be explained later) and an end margin which is provided with an inwardly curved recess 17 to serve as a bearing for the ball shaped end portion 18 of a rod 19. The other end 20 of this rod is slidably received in a bore provided in a small housing 21 which housing has a generally spherical end surface which is, in turn, received in a horizontally extending curved recess 22 formed in transversely extending member 23 attached to base 1 and spaced rearwardly from the end 16 of the pivotal lever 11.

15 Rod 19 is surrounded by a recoil helicoidal spring 24, the ends of which bear respectively against the end portion 18 of the rod and the housing 21 and, since the spring is under compression, tends to urge the housing 21 away from the end portion 18 at all times.

20 The rod 19 and the cooperating spring 24 act as a snap-action device which not only holds lever 11 in each of its two extreme positions, as exemplified respectively in FIGS. 1 and 2, but causes the lever to move almost instantaneously from one of these two positions to the other without noticeable delay.

The end 27 of the base 1 is provided with openings 30 to receive fastening members, such as screws 29, for attaching the gripping mechanism to a reciprocating arm 28 of a loom.

The operation is as follows:

25 During weaving of the cloth, the gripping mechanism, controlled by arm 28, FIG. 6, is introduced into shed 36 to engage the end of the weft thread 7 coming from a bobbin 37, with movable jaw 14 separated from stationary jaw 9, or in the open position, until it reaches the feed side of the loom, where the outer curved part of the movable jaw 14 hits stop 31, housed in loom frame 32.

30 Initially, movement of lever 11 in the clockwise direction causes the free end of the rod 19 to slide inwardly in the bore of housing 21 against the force of spring 24 until a medial point is reached between the extreme positions of the lever, at which point no further shortening of the distance between housing 21 and the ball shaped end 18 will occur. During all of the pivotal movement of lever 11 the ball shaped end 18 will merely pivot in the recess 17 but the spherical housing 21 at the other end of the rod, which was located at the outer end of curved recess 22 at the start of movement of the lever (FIG. 5), will not only pivot on the surface of the recess but will also engage in a slight transverse shifting movement in the recess (FIG. 4) at about the time the spring 24 has reached maximum compression due to shortening of the distance between the end portions of rod 19. At this position the pivot point 35 represented by recess 17 will pass over a line extending,

between the pivot point represented by housing 21 and the pivot point 10 of lever 11, allowing the spring 24 to begin expansion and urge the free end of rod 19 to slide out from the bore in housing 21 and in the process quickly continue the further clockwise movement of lever 11 until the end 16 of the arm has reached its extreme position, as shown in FIGS. 4 and 7, with the movable gripping jaw 14 in engagement with the stationary jaw 9 and gripping a weft thread 7 therebetween.

When the gripping mechanism, controlled by arm 28, pulling weft thread 7, returns and is introduced again into shed 36 and reaches the other side of the loom, FIG. 7, the projection of butt end 16 of arm 13 of lever 11, strikes stop 35 housed in loom frame 34, again causing compression and expansion of the recoil spring 24, and shifting of housing 21 but in the opposite direction, forcing end 20 of rod 19 to move inside its housing 21 and causing the instantaneous separation of mobile jaw 14 from stationary jaw 9, releasing weft thread 7. When the gripping mechanism makes its return trip, loose end 33 of weft thread 7 will slip through claw 15, said weft thread 7 being completely inserted along the entire length of the shed.

The details and characteristics used in embodying the objects of the present invention may be varied in accordance with the scope of the invention, and also the recoil helicoidal spring may be replaced by two facing magnets, located in the side wings of the lengthened base, all still being within the scope of the invention, as defined in the annexed claims.

I claim:

1. In a weft gripping means for a weft inserting element of a loom, the combination comprising an elongated base, one end

30

of the base being provided with a bayonet-shaped tip, a stationary jaw on said base adjacent said one end, a double-ended lever pivotally mounted at a medial point on said base, one end of said lever having an arm provided with a movable jaw coacting with said stationary jaw for gripping a weft thread therebetween when in gripping position, and spring means connected between said lever and said base for urging said lever selectively in either direction to hold said movable jaw in gripping or nongripping position.

10 2. The invention defined in claim 1, wherein said spring means includes a rod and a recoil helicoidal spring surrounding said rod, one end of said spring being connected with said double-ended lever, the other end of the spring being connected with said base.

15 3. The invention defined in claim 2, wherein said lever is provided with a recessed portion for receiving one end of said rod in swinging abutting engagement therewith, and said base is provided with housing means within which the other end of said rod is received in swinging and longitudinally slidable engagement.

20 4. The invention defined in claim 1, wherein said one arm of the lever is curved for engagement with a stop, said stop being provided at one side of a loom to urge said lever toward the gripping position.

25 5. The invention defined in claim 4, wherein the other end of said lever is curved for engagement with a second stop, said second stop being provided at the other side of a loom to urge said lever toward the nongripping position.
